UNITED STATES PATENT OFFICE.

FRANK WILTON CANTLEBERRY, OF SISQUOC, CALIFORNIA.

DEVICE FOR SUPPORTING COOKING UTENSILS.

1,414,771.

Specification of Letters Patent. Patented May 2, 1922.

Application filed October 24, 1918. Serial No. 259,565.

To all whom it may concern:

Be it known that I, FRANK W. CANTLEBERRY, citizen of the United States, residing at Sisquoc, in the county of Santa Barbara and State of California, have invented certain new and useful Improvements in Devices for Supporting Cooking Utensils, of which the following is a specification.

This invention relates to devices for supporting cooking vessels and has as its primary object to provide a device especially adapted for camp use in supporting pans, kettles, portable ovens, and, in fact, any and all types of cooking vessels which it may be desired to employ.

A further object of the invention is to provide a device for the purpose stated so constructed that the various vessels may be positioned upon the standard of the device at various elevations so as to be more or less closely positioned with relation to the flames, depending upon the commodity being cooked and the variations in temperature conditions found most desirable in cooking different commodities.

A further object of the invention is to so mount the utensil supporting members upon the standard of the device that these members may be adjusted vertically upon the standard at various elevations while supporting their respective utensils and without requiring the loosening and tightening of set screws or the manipulation of other devices for effecting such adjustment which it would be impracticable to manually grasp or otherwise manipulate because of proximity to the burning fuel.

Another object of the invention is to provide a device for the purpose stated which may be folded or otherwise collapsed to compact form when not in use and when being transported so that under such conditions it will occupy a minimum space and will not be cumbersome.

In the drawings:

Figure 1 is a perspective view of the device.

Figure 2 is a perspective view of one of the supporting members.

In the drawings the numeral 1 indicates the standard of the device, which standard is preferably in the nature of a cylindrical rod provided with a lower pointed end 2 which may be driven into the ground. In order that blows may be struck upon the

upper end of the standard for the purpose of driving its lower end into the ground and without likelihood of battering down or burring the upper end of the standard, the standard is reduced in diameter at its upper end as indicated by the numeral 3, and this reduced portion is threaded, as clearly shown in Figure 1 of the drawings. In reducing this end of the standard a shoulder 4 is formed and threaded onto the said end 3 of the standard is a head 5, the lower end of which, when the head is threaded into place, bears against the said shoulder 4. The upper face of the head, indicated by the numeral 6, is preferably flat. It will be understood that due to the abutment of the lower end of the head 5 against the shoulder 4, blows may be struck against the upper face of the head without likelihood of mutilating the threads by which the head is retained in place upon the standard so that removal of the head will not be at any time interfered with should it be desired to remove one or more of the utensil supporting members from the standard or fit other members to the said standard.

I have found it desirable to provide for mounting of the supporting members upon the standard in such manner that the members may be readily adjusted vertically along the standard so as to support the utensils at various elevations and may also be rotatably adjusted about the standard to position the various utensils more or less directly over the burning fuel or to shift the utensils from one side to another to obtain the most favorable results under varying conditions and with these objects in view I have provided devices for connecting the supporting members with the standard. Each of the supporting devices includes, in addition to the element provided for adjustable engagement with the standard of the device, an arm which is connected with and extends from the said element.

The said arm of the member is indicated by the numeral 23 and the same has secured to its opposite sides at its inner end, plates 24 which project beyond the said inner end of the arm in spaced relation to each other and extend at opposite sides of a lug 25 which projects radially from one side of a collar 26 having an opening 27 to slidably fit the standard 1. A pivot pin 28

is fitted through the ends of the plates 24 and through the said lug 25 and the lug at its end is turned downwardly to provide a nose 29 and has its upper side rounded as indicated by the numeral 30. The arm 23 likewise at its inner end is provided with a nose 31 and when the arm 23 is in horizontal position the nose 31 will abut against the nose 29 and the arm will be supported in said position although, of course, it may be swung upwardly upon the pivot 28 to extend beside the standard 1.

It will be understood that the supporting member as a whole may be rotatably swung about the standard as a center and that it may be shifted upwardly upon the standard or permitted to lower, and in order that the arm may be adjusted in this manner, without likelihood of burning one's fingers, an implement such as shown in Figure 1 and indicated in general by the numeral 15, is provided. This implement comprises a rod 16 formed at one end with a hook 17 which may be engaged beneath the arm 23 for the purpose of upwardly swinging the arm or for swinging the arm about the standard. The opposite end of this rod is preferably pointed as indicated by the numeral 18 thus

adapting the rod to be made use of as a barbecue hook if desired.

Having thus described the invention, what is claimed as new is:

In a device of the class described, a standard, a closed collar slidably and rotatably fitted upon the standard and adapted to be supported at positions of vertical adjustment thereon through the binding engagement of its wall against the surface of the standard, the collar having a shank portion projecting outwardly therefrom and terminating in a downwardly extending portion having a shoulder, spaced members projecting from the opposite sides of the said portion and pivoted thereon, and a supporting arm mounted between the spaced members and having a downwardly projecting portion located adjacent to and providing a shoulder for abutment against the first mentioned shoulder whereby to limit the downward swinging movement of the arm upon its pivot, the arm being movable in an upward direction upon its pivot to extend beside the standard in folded position.

In testimony whereof I affix my signature.

FRANK WILTON CANTLEBERRY. [L. S.]
